UNITED STATES PATENT OFFICE.

BENJAMIN J. COHON, OF WESTWOOD, AND LOUIS MOSKOWITZ, OF BAYONNE, NEW JERSEY.

LOCK.

1,351,838.

Specification of Letters Patent. Patented Sept. 7, 1920.

Application filed May 8, 1916. Serial No. 96,105.

To all whom it may concern:

Be it known that we, BENJAMIN J. COHON and LOUIS MOSKOWITZ, citizens of the United States, residing at Westwood, in the county of Bergen and State of New Jersey, and Bayonne, in the county of Hudson and State of New Jersey, respectively, have invented certain new and useful Improvements in Locks, of which the following is a specification.

Our invention relates to an improvement in locks; particularly locks of the type comprising a bolt, and mechanism for causing the bolt to be shot into engaging position with respect to a strike-plate, and be withdrawn from the same.

In our application for a patent on a lock; Serial Number 74,631, filed January 27, 1916, and allowed March 30, 1916, we have set forth a device comprising a bolt and a carrier therefor adapted to be actuated by cams in such a way as to prevent the return or withdrawal of the parts, except by reverse movement of the cams. The lock disclosed in this application is of similar construction; but is especially designed to be secured to the inner side or face of a door, rather than be mortised in the edge thereof; and it has its parts so shaped that they can be mounted on either right or left hand doors, in position to operate as desired. Further, the carrier and bolt are positively actuated to be moved to or from locking position, with practically no lost motion, after the carrier and bolt once begin their forward or rearward displacement; and when the bolt is even partially shot, it cannot be pushed back by means of a tool from without; or in any other way except by giving reverse movement to the cams through a considerable arc of travel.

The above and other objects and advantages of our invention will appear from the following description, taken in connection with the accompanying drawings; and be precisely defined in the appended claims. But the disclosure herein is explanatory only, and the basic principle of our invention may be embodied in other constructions that are similar in effect, as indicated by

differences in the modes by which the characteristics of our improvement, as stated in the several claims, are expressed. On the drawings,

Figure 1 is a view showing our improved lock mounted on a door that is arranged to open in one direction;

Fig. 2 is a similar view, illustrating our lock in position to be applied to a door hinged so as to open by movement in a different direction;

Figs. 3, 4 and 5 are diagrammatic views showing the parts of our lock in various operative positions;

Fig. 6 is a transverse, vertical section taken through the mechanism and the inclosing casing of our lock; the plane of section being indicated by the line 6—6 on Fig. 3; the observer looking in the direction of the arrow;

Fig. 7 is a horizontal, longitudinal sectional view of the mechanism of our lock, taken on the line 7—7 of Fig. 1; and

Fig. 8 is a perspective of a strike plate constituting part of our invention. The same numerals of reference identify the same parts throughout.

To describe our lock, we shall first direct attention to Figs. 1, 6, 7 and 8. On the views named, the numeral 1 indicates a portion of a door frame and 2 a portion of a door, hinged to the frame 1 in the usual way. To the inside of the frame is secured a strike plate 3, which is in position to be engaged by an element, such as a bolt 4. This bolt is mounted in a casing 5 fastened to the door on the inner side or face of the latter; that is, the side or face which is turned toward the interior of the room or dwelling to which the door is attached. This casing constitutes not only a housing, but also means for supporting the mechanism by which the bolt 4 is operated. In Fig. 1, the door is shown as being hung so that it opens to the left; but in Fig. 2, the lock is shown in readiness to be applied to a door so arranged that it opens to the right; and both these views illustrate the door as located between the casing 5 and the observer. One side of the casing 5 may be

open; that is, not permanently closed; and this side will be in direct contact with the door when the casing is fixed in place. This open side may be closed by a removable plate, lying flat against the door; not shown in Fig. 1, but included in Figs. 6 and 7; to be referred to again later.

Inside the casing 5 is a carrier 6, movable longitudinally of the casing; that is, horizontally when the casing is mounted on the door 2; by means of a revoluble member such as a cam 7; which is received in a central opening 8 of the carrier 6. The carrier bears the lock bolt 4, which has portions constituting transverse ribs 9 on both faces to engage the front and rear ends of the carrier; and is provided with a central opening 10 to receive a controlling means, such as a cam 11. The cams 7 and 11 are both rigid with a shaft 12, which is mounted in a bearing in the casing, and is somewhat flattened at its inner end to be enabled to engage the cams and turn them. At one end the bolt 4 is extended beyond the ribs 9 and the carrier 6; providing a terminal portion having a lateral projection 13. This terminal portion is movable longitudinally through an aperture 14 in the forward end of the casing and through a similar aperture 15 in the strike-plate 3, aligned with the aperture 14; and when the terminal portion of the bolt has moved far enough to enable the projection 13 to clear the plate 3, it is operated to move transversely to cause the projection to pass behind the lower edge of the opening 15 and secure the door in closed position. The form of the projection 13 is not material. It may be shaped in almost any way so as to leave a space or recess between it and the forward ribs 9 or body of the bolt 4.

The shaft 12 may be provided with a knob on its end outside the casing 5 to be turned by a person inside the room or dwelling; and the door may also carry on its outer side or face a suitable tumbler or cylinder lock construction, to be described later in full, operable to engage and turn the shaft when the proper key is inserted.

Fig. 1 shows the position of the parts when the bolt is shot from the casing, and Fig. 3 illustrates the lock when the operation of withdrawing the bolt has commenced. Fig. 4 shows the bolt retracted completely. If one takes these three views in reverse order, the mode of operation of our lock will become plain. The cam 7, moving from the position shown in Fig. 4, first acts on the carrier to push it toward the opening 14; and the cam and carrier together then serve as means for actuating the bolt to enable it to be moved translationally in one direction; that is, longitudinally of the casing. The cam 11 at this time holds the bolt 4 against

movement with respect to the carrier till the carrier reaches the forward end of the casing 5, in which the opening 14 is located. Further rotation of the shaft 12 will now enable the bolt 4 to be moved translationally in another direction; that is, transversely of the carrier and the casing, as indicated in Fig. 3; so that the projection passes behind the strike-plate and finally comes to rest, as in Fig. 1. Fig. 5 omits the bolt, to show the cam 7 and the carrier 6 more clearly in the positions given by Fig. 4.

The open side of the casing, which is presented to the observer in Fig. 1, is fitted with a removable plate 16; shown in Figs. 6 and 7. This plate closes the casing and lies against the door, as above stated. As clearly seen in most of the views, the carrier is as wide as the casing; so that only longitudinal movement of the carrier in the casing is permitted; all likelihood of transverse movement being eliminated. The opening 8 is substantially quadrant-shaped; with one edge almost straight and parallel with the rear edge of the carrier, and adjacent thereto; and with another edge located near the lower edge of the carrier and extending forward. The edge of the opening 8 between the ends of these two edges is curved on the arc of a circle, whose center will be in the axis of the shaft 12 when the carrier occupies the positions shown in Figs. 1, 2, 3 and 7. The ribs 9 of the bolt 4 are spaced apart a distance slightly greater than the distance between the front and rear edges of the carrier; whereby the bolt cannot move longitudinally of the casing except in unison with the carrier; but can move transversely thereof when the cam 11 has been revolved to a predetermined extent. The central opening 10 of the bolt 4 is elongated, terminating at the forward ribs 9; but does not extend as far back as the rear ribs 9.

I prefer to make the cam 7 of the form shown, with a rear edge 17 that is substantially straight or radial; and a forward edge 18 that is curved on the arc of a circle having its center at the axis of the cam; and terminates in a nose 19, located between the extremities of the cam. The cam 11 is shaped like an equilateral triangle with its sides curving outward slightly and its corners rounded. It is secured to the shaft adjacent one corner; and its radially extending sides are indicated by the numeral 20 and the remaining side by the numeral 21; this side also being curved on the arc of a circle having the axis of the cam as a center. In order to make these cams operate as required, they are mounted in such angular relation on the shaft 12 that the side 21 of the cam 11 is spaced away from the edge 17 of the cam 7, and extends at an angle thereto; and the rear rounded corner of the cam

11 will be in proximity to the nose 19. Both cams have openings to receive the flattened inner end of the shaft 12.

When the bolt is withdrawn, the cam 7 will extend straightaway from the opening 14, holding the carrier 6 and the bolt 4 as far toward the rear end of the casing as they will go. The terminal portion of the bolt 4 having the projection 13 now lies wholly within the casing, in line with the openings 14 and 15, but not protruding from the casing; while the bolt as a whole is held up near the top of the edge of the carrier by the cam 11, which will be located in the front end of the opening 10; near the adjacent ribs 9, with its edge 21 nearly horizontal. The first movement of the shaft 12 impels the carrier and the bolt together toward the front of the casing, but the bolt is held against movement across the casing by the cam 11 till the cams have revolved about 90 degrees. Movement of the cams to this extent will thrust the carrier and the bolt to the extreme front of the casing, as indicated in Fig. 3. Further rotation then causes the curved edge 18 of the cam 7 to sweep along the inside of the circularly curved edge of the opening 8, without exerting any further force on the carrier 6. Meanwhile the cam 11 moves its curved face 21 downward, away from the upper edge of the opening 10 in the bolt, with its outer corners engaging the bolt. Hence the bolt can be controlled to enable the projection 13 to move behind the plate 3, as depicted in Fig. 1.

The lock operates in this manner when applied to a door that opens to the left, as in Fig. 1. When mounted on a door that opens to the right, it operates in the same way, but the parts must first be rearranged. By scrutinizing Figs. 1 and 2, one can see that, to be able to fix the casing to the door shown in Fig. 2 so that the side of the casing with the plate 16 will lie against the door, the casing has to be turned in a vertical plane through half a circle to make its ends change places and put the opening 14 at the left, instead of at the right. Such a change of position would make the projection 13 point upward. The bolt and the carrier must accordingly be turned over; the former about a horizontal axis and the latter about a vertical axis; and the cams 7 and 11 must be similarly manipulated by slipping them off the flattened end of the shaft 12 and replacing them as needed. The sides of the bolt and the carrier and the cams presented to the observer in Fig. 1 are indicated by the letter A. After being turned in the manner just set forth, the parts in question will present their opposite sides, indicated by the letter B. The cams will be fixed to the shaft 12 in the same angular relation as before;

and will produce the same result when rotated. As the carrier and the cams are flat, and as the bolt has transverse ribs 9 on both faces, the operation of adjusting the parts for a right hand door or a left hand door is simple and easy.

It is apparent from Fig. 1 that the bolt 6 must go from left to right as it moves longitudinally of the casing when the latter is secured to a left hand door; but when the positions of the carrier, the bolt, and the cams are changed with respect to the casing, so as to adapt the lock to be applied to a right hand door, as in Fig. 2; the bolt 4, as it moves longitudinally in the casing, must travel in the opposite direction; that is, from right to left. The movement of the bolt transversely of the casing, after the projection 13 enters the strike-plate, is in the same direction in both cases; that is, downward.

The strike-plate 3, illustrated fully in Figs. 7 and 8, is secured to the inside of the door frame 1 and has a part projecting beyond the face 22 of the frame. This part contains the opening 14. From the face of the plate beside the opening 14 extends a projection 23, the ends of which are joined to the plate 3 by the webs 24. This projection fits against the face of the frame 1, and both the projection and the plate can be made fast by screws or the like. This strike-plate is preferably cast in one piece, and can be used on either right or left hand doors by turning it about. When the bolt is shot through the plate 3, the projection 13 becomes visible from the inside of the room or dwelling; whereby the occupant can see if the lock has been properly manipulated when the door is to be made fast.

It will now be seen, regardless of the kind of door on which the lock is mounted, that when the bolt is shot forth as in Figs. 1 and 2, the cam 11 contacts with the lower edge of the opening 10 directly below the shaft 12. Hence a force applied to lift the bolt so as to bring the projection 13 into line with the projections 14 and 15 must be exerted straight through the axis of the shaft 12; and no leverage whatever is afforded. Hence, there is no possibility of the bolt being moved back by a "jimmy" or other burglar's tool. The cam 7 holds the carrier 6 against rearward movement in the same way.

To withdraw the bolt, the shaft 12 is turned in the reverse direction, causing the cam 11 first to lift the bolt 4 into position to make the projection 13 clear the lower edge of the opening 15 in the strike-plate 3. While this movement is being produced, the cam 7 continues to hold the carrier 6 against rearward movement, even if a considerable force from without be applied, by reason of the curved edge 18 engaging the curved part

of the edge of the opening 8. Since this curved edge 18 is circular with reference to the shaft, such a force, even if exerted horizontally, will give rise to a reactive force at the point of contact between the cam 7 and the curved edge 18 of the opening 8 that is normal to the edge 18, and therefore radial; passing through the axis of the shaft 12. Hence, a force tending to move the carrier 10 back into the casing can have no leverage and produce no movement of the carrier for any position of the cam 7 between that shown in Fig. 1 and that shown in Fig. 3. The carrier and the bolt are thus secured 15 against longitudinal movement till the bolt 6 is fully lifted, and opening the lock by tampering from the outside is absolutely impossible. Only by the instrumentality of the shaft 12, moving back the cam 7 through 20 a considerable arc of travel before the bolt can be made to return to the rear end of the casing, can the lock be opened.

The particular advantage of this action of the cam 7 resides not only in the fact 25 that the carrier will prevent the bolt, after engaging the strike-plate with its projection 13, from being pushed back into the casing, should any one succeed in lifting the bolt with a tool far enough to enable 30 the projection to clear the lower edges of the openings 14 and 15; but also in the circumstance that the lock will efficiently hold the door if the shaft 12 is not turned far enough. That is to say, if, from any cause, 35 both cams are not thrown over to the limit of their travel; so that, for example, they stop a little beyond the position shown in Fig. 3; the bolt will still engage the strike-plate in a manner that will preclude the 40 possibility of the door being opened again, except by turning back the shaft and returning the cams to the starting point. When the bolt is shot, the nose 19 fits into a recess along the lower edge of the opening 45 8.

It is also to be noted that, as soon as the movement of the carrier is commenced by the cams, all lost motion is eliminated. It is true that the shaft 12 may require to be 50 rotated through a slight angle before the cam 7 can engage the curved forward edge of the opening 8, as indicated in Fig. 4; but once this angle is traversed, and the motion of the carrier and bolt toward the 55 forward end of the casing is begun, the carrier and the bolt are positively controlled and actuated by the cams at every point till their respective motions are completed. The fact that the shaft 12 may be turned to 60 some extent before the carrier and the bolt can be set in motion is rather an advantage because it makes a deliberate, intentional turn of the shaft necessary to start the lock into operation; and a slight, casual twist 65 of the knob on the shaft 12 will not actuate

the lock. When the carrier and the bolt are retracted, they are positively controlled by the cams all the way back to starting position. Of course, the opening 8 may be so shaped that the cam 7 may contact with the 70 carrier the instant the cam starts from its position in Fig. 4.

The shaft 12 is round except for its flattened inner end and extends through a bearing in the back of the casing; and the knob above mentioned is fast on its outer end and is indicated in Figs. 6 and 7 by the numeral 25. This knob will be shaped so that it is substantially flat on the side which is presented toward the casing; or it may be 80 shaped in any other way that will enable the peripheral portions of that side to be no farther from the casing than the portions near to the axis or center of the knob. Between the knob and the casing is a sleeve 85 26, the outer end of which fits loosely into a groove 27 on the face of the knob presented to the casing; and the other end is fixed to the casing 5. In this case, the sleeve serves as a bearing for the shaft; and, besides, it covers and protects the shaft and prevents access thereto between the knob and the casing. Thus this sleeve renders it impossible for any one boring through the door beside the casing to engage the shaft 95 from the outside of the door; and turn the shaft by mechanical means. The groove 27 may of course be omitted, and the sleeve simply extended up to the adjacent face of the knob. The same protective effect will 100 be afforded if the sleeve is not fixed to the casing, but simply hangs loosely on the shaft; so long as it covers the whole of the shaft that is outside of the casing 5. When the sleeve is fixed, as shown, the shaft 12 105 may have a circumferential groove 28 covered by the sleeve 26, to be engaged by a screw 29 in the sleeve 26. This screw will permit the shaft to turn freely, while preventing axial displacement of the shaft, or 110 its withdrawal from the casing.

The lock herein described can also be mounted on a door by cutting a mortise or recess in the edge thereof, and inserting the casing 5; thereby making the lock serve as a 115 mortise lock. In this instance, a different form of strike-plate will be needed. The lock can also be employed on windows, desks, etc., as well as upon doors.

The casing, with the cams, the carrier, 120 and the bolt can all be made by stamping; whereby the lock can be manufactured very cheaply; and assembled in very little time. We also make by stamping an arm 30, to be fixed on the shaft 12 in the casing, between 125 the casing and the carrier, in position to be pressed upon by a spring 31, mounted on the back of the casing 5. This arm extends out from both sides of the shaft, and will be parallel to the line of movement of the 130

bolt, when the bolt is fully shot or withdrawn. It turns with the shaft, and against the force of the spring 31 as the bolt is moved out and in; and if the knob should be released before the bolt has completed its throw toward or from the strike-plate, the pressure of the spring 31 acts on the arm to turn the shaft far enough to insure the bolt 4 reaching the limit of its movement in either the forward or reverse direction. The arm and spring, however, are not essential parts of our invention, and both may be omitted.

The lock will be capable of being opened 15 from the outer side or face of the door 2, by means of an ordinary tumbler or cylinder lock construction 32, shown in Figs. 6 and 7. This lock will be mounted in a hole in the door, and will have a tongue 33, polygonal in cross section, projecting into the casing 5. The plate 16 of the casing will have a circular central opening receiving a bushing 34 in line with the tongue 33. This bushing will have a collar at its outer end, 25 and be threaded at the other to receive a nut 35; plate 16 being between the collar and the nut; whereby the bushing will be held fast to the plate. The bore through the bushing will correspond in shape to the 30 cross section of the tongue 33. We mount the bushing to turn freely in the plate; so that the tongue 33 may rotate the bushing. The nut above mentioned carries a radial arm 36; and on the adjacent end of the 35 shaft 12 is rigidly carried an arm 37, having its outer end bent over, as at 38, toward the plate 16. When the proper key is inserted into the cylinder lock 32, the tongue 33 can be revolved to turn the arm 36 over to engage the end 38 of the arm 37, to shoot or withdraw the bolt. The cylinder lock, as will be understood, comprises an inclosing case, containing a round body which is held fast by tumblers till the proper key is inserted, and then the round body in question can be rotated in the casing. This round body is rigid with the tongue; and at its outer end this tongue will project into a 45 round bore in the inner end of the shaft 12. There is of course no connection between the inside of the shaft 12 and the tongue 33; so that the turning of the shaft by the knob 25 does not rotate the tongue. The lost motion connection between the arm 36 and 50 the arm 37 permits the bolt 4 to be operated by the shaft 12 independently of the tumbler lock mechanism.

The arm 37 has such a form as to fit over the inner end of the shaft 12, as shown in 60 Figs. 1 to 5 inclusive; and it may likewise be made by stamping. Two small screws serve to hold the arm removably on the shaft. When the bolt and the carrier, with the cams, are to be turned over to fit a door 65 opening in a different direction, the screws

are removed, the position of the parts changed, as above described, and the arm again put on the shaft in the same position with respect to the cams and the casing as before, and the screws reinserted. The cams 70 will be on the shaft 12 between the arm 37 and the arm 30; and be gripped by both; and the threads for each screw will be half on the inside of the arm 37 and half on the outside of the shaft 12, providing two semi-cylindrical threaded bores which together 75 make up a cylindrical opening, into which the screw can readily be fitted; one such opening being made in this way for each screw. The arm 37 therefore serves the additional purpose of keeping the cams 7 and 11 tight on the shaft 12.

The casing will be held to the door by screws or bolts inserted through holes at the corners of the casing; or by any other suitable means. Further, the longitudinal edges of the carrier will be engaged by 85 guide projections 39 adjacent the back of the casing to maintain the carrier in the plane of the cam 7; and similar projections 40 on the inner face of the plate 16 will prevent the bolt from getting out of the plane 90 of the cam 11. These projections are indicated in Fig. 6. Thus the movement of the carrier and the bolt will be restricted, and 95 all risk of lateral displacement toward the plate 16 or the back of the casing obviated. The casing may be specially shaped to provide the projections 39 and 40; which will have the form and location necessary to 100 give the desired effect.

Having described our invention, what we believe to be new and desire to secure and protect by Letters Patent of the United States is:—

105

1. The combination of an element having a locking projection, means for actuating said element to enable it to be moved translationally in one direction, means for controlling said element to enable it to be moved 110 translationally in another direction, and means for supporting said element, said actuating means and said controlling means in operative relation; said element, said actuating means and said controlling means 115 being so shaped that, upon the positions of the element, the actuating means and the controlling means being changed with respect to said supporting means, said element can be moved in a direction opposite to the 120 one direction when the actuating means is operated, and in the same direction as the other direction when the controlling means is operated.

2. The combination of an element having 125 a locking projection, means comprising a revoluble member for actuating said element to enable it to be moved translationally in one direction, means for controlling said element to enable it to be moved translation-

130

- ally in another direction, said controlling means preventing movement opposite to the last-named direction except upon reverse movement of said controlling means, and said actuating means preventing movement of said element opposite to the first-named direction, except upon reverse movement through a considerable arc of said revoluble member.
- 10 3. The combination of an element having a locking projection, means comprising a revoluble member for actuating said element to enable it to be moved translationally in one direction, means for controlling said element to enable it to be moved translationally in another direction, said means engaging said element so as to eliminate substantially all lost motion between said element and said means after said element is set into motion by said means, and means for supporting the element and the actuating and controlling means.
- 15 4. In a locking mechanism, a bolt comprising a terminal portion having a locking projection, said bolt being provided with a pair of parallel ribs on one face and a pair of parallel ribs on the opposite face, and having an elongated opening therein between said ribs.
- 20 5. In a locking mechanism, the combination of a shaft, a cam having a circularly curved edge terminating in a nose, on said shaft, and a triangular cam on the shaft having one corner located adjacent said nose, and between the lateral edges of the cam bearing said nose.
- 25 6. The combination of an element having a locking projection, a carrier therefor, said carrier having an opening with a circularly curved edge, a cam in said opening having a circularly curved edge adjacent its outer end to engage the curved edge of the opening to actuate the carrier, and prevent the return thereof except upon reverse movement through a considerable arc of said cam, and means for moving the element with respect to the carrier.
- 30 7. In a locking mechanism, the combination of a locking element, a shaft having means for moving said element, an arm secured to the shaft to hold said means in operative position, and means for engaging the arm to turn the shaft.
- 35 8. In a locking mechanism, the combination of a locking element, a shaft having means for moving said element, an arm fitted upon the end of the shaft, screws between the arm and the shaft to hold said arm and said means in operative position, and means for engaging the arm to turn the shaft.
- 40 9. The combination of a casing, a locking
- element therein, a shaft terminating within the casing for moving said element, said shaft having a circular bore at its inner end, 65 a bushing rotatably carried by the casing in line with the shaft and having a polygonal opening, and means providing a lost motion connection between the shaft and the bushing.
- 10 10. The combination of an element having a locking projection, means comprising a carrier for the element, to actuate the latter to enable it to be moved translationally in one direction, means for controlling said 75 element to enable it to be moved translationally in another direction; and means for supporting said element, said actuating means and said controlling means in operative relation; said element, said actuating 80 means and said controlling means being so shaped that, upon the positions of the element, the actuating means, and the controlling means being changed with respect to the supporting means, said element can 85 be moved in a direction opposite to the one direction when the actuating means is operated, and in the same direction as the other direction when the controlling means is operated.
11. The combination of an element having a locking projection, means comprising a carrier and a revoluble member for actuating said element to enable it to be moved translationally in one direction, means for 95 controlling said element to enable it to be moved translationally in another direction, said controlling means preventing movement opposite to the last-named direction except upon reverse movement of the controlling 100 means, and said actuating means preventing movement of the element opposite to the first-named direction, except upon reverse movement through a considerable arc of said revoluble member.
12. The combination of an element having a locking projection, means comprising a carrier and a revoluble member for actuating said element to enable it to be moved translationally in one direction, means for 110 controlling said element to enable it to be moved translationally in another direction, said means engaging said element so as to eliminate substantially all lost motion between said element and said means after 115 said element is set into motion by said means, and means for supporting the element and the actuating and controlling means.
13. In testimony whereof we have signed our 120 names to this specification this 5th day of May, 1916.

BENJAMIN J. COHON.
LOUIS MOSKOWITZ.
